VALVE ACTUATOR FOR A URINARY DRAINAGE BAG OR THE LIKE

Robert Dyall Flinn, Libertyville, Ill., assignor to
Abbott Laboratories, North Chicago, Ill.

Filed Feb. 25, 1975, Ser. No. 552,812

Term of patent 14 years

Int. Cl. D23—01

U.S. Cl. D23—19

FIG. 1.

FIG. 2.

FIG. 3.

FIG. 1 is a perspective view taken from one end of a valve actuator for a urinary drainage bag or the like showing my new design;

FIG. 2 is a perspective view taken from the end opposite that shown in FIG. 1; and

FIG. 3 is a side elevational view thereof.

I claim:

The ornamental design for a valve actuator for a urinary drainage bag or the like, substantially as shown.
